DESIGN FOR AN EARRING OR SIMILAR ARTICLE

Leonard G. Arpin, Montclair, N. J.

Application December 17, 1946, Serial No. 135,573

Term of patent 3½ years

(Cl. D45—9)

To all whom it may concern:

Be it known that I, Leonard G. Arpin, a citizen of the United States, residing at Montclair, in the county of Essex and State of New Jersey, have invented a new, original, and ornamental Design for an Earring or Similar Article, of which the following is a specification, reference being had to the accompanying drawing, forming part thereof.

In the drawing

Fig. 1 is a front elevational view of an earring or similar article, showing my new design.

Fig. 2 is a side elevational view thereof, the ear-engaging member being shown in broken lines.

I claim:

The ornamental design for an earring or similar article, as shown.

LEONARD G. ARPIN.
